UNITED STATES PATENT OFFICE

2,186,004

BURNER FOR LIQUID FUEL

James L. Breese, Santa Fe, N. Mex., assignor to
Oil Devices, Santa Fe, N. Mex., a limited partnership of Illinois

Original application February 8, 1937, Serial No.
124,695. Divided and this application March
14, 1938, Serial No. 195,728

2 Claims. (Cl. 158—91)

My invention relates to an improvement in burners for burning liquid fuels, such as hydrocarbons, and has for one purpose the provision of a burner which can be turned down to a very small fire, or low draft, without destroying the characteristic mode of combustion described, for example, in my prior issued Patent No. 1,702,929, issued on February 19, 1929.

Another purpose is the provision of means for permitting low drafts burning with such a burner, while preventing down drafts from upper portions of the combustion chamber, which would disadvantageously affect combustion.

Another purpose is the provision of such means which are adaptable for ready removal to permit easy cleaning of the burner and for adjustment of the burner capacity.

Another purpose is the provision of a burner for carrying on my characteristic combustion method which constitutes or includes a plurality of superposed burners of varying diameters.

Another purpose is the provision, in connection with one of my burners, of a lower supplementary burner which may have the functions of a pilot light for maintaining combustion during periods when a minimum heat or no heat is desired.

Another purpose is the provision of means for locating a lower baffle sufficiently low in the burner to maintain a minimum flame as a pilot with a minimum use of fuel.

Another purpose is the provision of means for raising such lower baffle to a level sufficient to render it easy to initiate combustion, while permitting its ready return to turndown position.

Other purposes will appear from time to time in the course of the specification and claims.

The present application is a division of my copending application Serial No. 124,695, filed February 8, 1937.

I illustrate my invention more or less diagrammatically in the accompanying drawing, wherein:

Figure 1 is a vertical axial section;

Figure 2 is a similar section of a variant form of the device.

Like parts are indicated by like symbols throughout the specification and drawing.

Referring to the drawing, 1 generally indicates an outer furnace or heater shell and 2 an inner shell. 3 is a horizontal partition secured to the inner shell and provided with a central aperture 4. 5 is a preferably removable baffle, with a central aperture 6. 7 is a combustion chamber member, herein shown as generally cylindrical,

with a bottom 8 which may be formed, if desired, in one piece and may be secured in any suitable way, as by bolts or welding 9, to the member 3.

10 is any suitable fuel supply pipe extending to the bottom 8. The means for supplying the fuel is not herein shown since it does not of itself form part of the present invention, but it will be understood that any suitable float chamber or the like may be employed for governing the desired flow of fuel, for example a liquid hydrocarbon fuel, to the bottom 8.

11 is a closure member secured within the shell 2 and provided with apertures 12, which may be in a separate removable plate 13 closing the central aperture 14 of the member 11. I herein illustrate air inlet apertures 15 in the bottom of the shell 2 and it will be understood that any suitable means, whether by natural draft or forced draft, may be used to supply air to the space between the shells 1 and 2, which air is caused to flow through the apertures 15, upwardly through the apertures 12, and into the space between the member 7 and the shell 2. The member 7 is provided with an upper row of secondary air inlet apertures 16, herein shown as upwardly and inwardly inclined. A plurality of preferably smaller apertures 17 are shown arranged in rows in a lower portion of the member 7. The bottom row 18 is also indicated.

Positioned above the bottom row 18 is an upwardly movable and removable ring 19, herein shown as a simple annular disc conforming generally to the inner face of the wall 7 and having a central aperture 20. It may normally be positioned in lowest position by permitting it to rest by gravity upon any suitable inward projections, studs or the like, 21. If desired, there may be a slight clearance of the outer edge of the baffle ring, inasmuch as I find it advantageous to permit the certain flow of air upwardly along the inner face of the wall 7. This clearance may vary and may be as much as an eighth to a quarter of an inch if desired.

In the form of Figure 2, in the place of the studs 21, I may provide a lower portion of the chamber of reduced diameter as at 22, which is connected to the portion 7 as by a generally horizontal shelf or ledge 23, upon which the baffle 19 may rest by gravity when in its lowermost position.

In the normal operation of the device, the characteristic combustion method of my Patent Number 1,702,929 may be carried on. The primary air supply enters through the apertures 17 and 55

mingles with the hydrocarbon vaporized by combustion. The heat of combustion, once the device is in operation, vaporizes the hydrocarbon and the vaporized hydrocarbon rises and mixes with the primary air supply to form a primary mixture. This primary mixture moves upwardly toward and through the aperture 6 of the baffle 5 and there receives the secondary air supply admitted through the apertures 16. This produces a final mixture which burns and provides the heat for the stove or furnace unit.

Preferably, whether by natural draft or by any suitable fan or the like, not herein shown, sufficient air is admitted for maintaining combustion at a rate sufficient to give the desired heat. Any suitable control means, thermostatic or otherwise, may be employed for controlling the desired heat produced.

In the event that it is desired to turn down the unit to a minimum heat, or to practically no heat, the air supply is reduced and combustion is correspondingly reduced. In the structure as shown in my Patent Number 1,702,929, there is a limit below which the stove does not operate efficiently. For example, unless a sufficient air supply and sufficient rate of combustion is maintained, the secondary air or the air above the baffle 5 tends to eddy back and circulate down into the primary combustion zone, with the result that the balance between the primary and secondary zones is destroyed and my method of combustion is interrupted, resulting in carbon deposit, and inefficient combustion.

I find that the interposition of a baffle, such as the one shown herein at 19, prevents this down draft and my primary mixing and combustion may be carried on by means of the holes 18, and the secondary air may then be supplied by some or all of the holes 17. In other words, the primary zone moves down to or is limited to the holes below the baffle, and the holes above the baffle, which previously operated as a source of primary air, then becomes the source of secondary air.

When the baffle 19 is at the bottommost position in which it is shown in the figures, the portion of the chamber below the baffle becomes a very effective pilot light structure which employs a very small amount of fuel. The smaller the opening 20 in baffle 19 the lower the minimum flame and the greater the turndown. There is, however, a critical point in the size of the aperture taken with the position of the baffle 19 at which, even though it will satisfactorily maintain a flame after the device is in combustion, it will not permit combustion to initiate.

I initially raise the baffle 19. This allows an increased supply of air to enter the space below the baffle which is important in the initial period of combustion. The size of the central hole 20, which determines the minimum combustion, may be made quite small, if means are provided for raising the baffle during the period of initiation. For example, if I employ a 10 inch burner with a two inch hole in the baffle 19 and it is difficult to light the burner because of insufficient air in the lowest zone, I simply lift the

baffle 19 to a higher position and permit a larger number of air apertures to communicate with the space below the baffle. This prevents the mixture below the baffle from becoming so rich that the flame dies out before the burner is properly lighted.

I may employ a variety of means for raising the baffle 19, but I illustrate a chain 40 passing over any suitable roller 41 extending out to any suitable handle 42. The lower end of the chain may be secured to the baffle 19 by any suitable means. I illustrate for example chain branches 43. It will be understood that a pull on the handle 42 serves to raise the baffle. The baffle may be kept in raised position by engaging the chain or handle by any suitable abutment mechanism generally indicated at 44.

It will be realized that whereas I have described a practical and operative device, nevertheless many changes may be made in size, shape, number and disposition of parts. I therefore wish my drawing to be taken as in a broad sense illustrative or diagrammatic rather than as limiting me to the specific structure herein described and shown.

I claim:

1. A mechanism for burning liquid fuel, which includes a perforated walled chamber having a wall with air admission apertures therein, means for admitting a liquid fuel to the chamber, said chamber having an open top, a baffle normally located adjacent the bottom of the chamber but above the lowest said apertures, said baffle having an aperture therein, the size of the aperture in relation to the form and cubic content of the chamber, and the height of the baffle from the chamber bottom, being adapted to maintain combustion within the portion of the chamber below said baffle when combustion has been initiated, but being insufficient to permit combustion to be initiated, means for bodily raising said baffle to a sufficient height to permit the initiation of combustion, whereby, when the baffle is so raised, additional air inlet apertures are put in communication with the portion of the chamber below said baffle, and for holding said baffle fixed in adjusted position.

2. In a device for burning liquid fuels, a mixing pot having a perforate wall, a baffle adapted to divide said pot into an upper and a lower chamber, said baffle being apertured to put said two chambers into communication with each other, means for normally supporting said baffle in a lower portion of said pot, whereby the volumetric capacity of the chamber below the baffle is substantially less than the volumetric capacity of the chamber above said baffle, means for bodily raising said baffle to a higher position and for thereby changing the relative volumetric capacities of the two chambers, and at the same time placing the space below the baffle in communication with additional apertures, whereby the air supply to the lower chamber is increased, as well as its volumetric capacity, and means for fixing the baffle in adjusted position.

JAMES L. BREESE.
